HEADSET FOR DICTATING MACHINES

William J. O'Neil, New York, N. Y., assignor to Dictaphone Corporation, Bridgeport, Conn., a corporation of New York

Application September 25, 1951, Serial No. 16,737

Term of patent 14 years

(Cl. D26—14)

To all whom it may concern:

Be it known that I, William J. O'Neil, a citizen of the United States, residing in New York, in the county of New York and the State of New York, have invented a new, original, and ornamental Design for a Headset for Dictating Machines, of which the following is a specification, reference being had to the accompanying drawing, forming a part hereof.

The fragmentary dotted line disclosures of cord and plug attachment shown in Figure 1 is for illustrative purposes only.

The dominant features of my design reside in those portions shown in full lines.

I claim:

The ornamental design for a headset for dictating machines, substantially as shown and described.

WILLIAM J. O'NEIL.
